UNITED STATES PATENT OFFICE.

CHARLES F. PIKE, OF PHILADELPHIA, PENNSYLVANIA, ASSIGNOR TO THE NATIONAL ANTI-SEWER GAS COMPANY, OF CAMDEN, NEW JERSEY.

WATER-CLOSET.

SPECIFICATION forming part of Letters Patent No. 271,356, dated January 30, 1883.

Application filed August 7, 1882. (No model.)

To all whom it may concern:

Be it known that I, CHARLES F. PIKE, a citizen of the United States, residing at Philadelphia, in the county of Philadelphia and State of Pennsylvania, have invented certain new and useful Improvements in Water-Closets, of which the following is a specification, reference being had therein to the accompanying drawing.

10 My invention has relation to that class of water-closets wherein a disinfecting-liquid is introduced into the bowl or retainer while the latter is being flushed. Such closets have heretofore been so constructed that when operated 15 the disinfectant passes into the bowl or retainer simultaneously with the flushing-water, the result whereof is that the disinfectant, commingling with the flushing-water, is carried out of the retainer and the trap by the siphoning 20 of the latter without accomplishing to any great degree the purpose for which its use is designed. My invention has for its object to avoid such disadvantage by introducing the disinfectant into the bowl or retainer after the 25 flushing operation is accomplished, so as to obtain a disinfectant seal for the trap, and thereby obtain the fullest beneficial results from the use of such liquid.

30 My invention accordingly consists of the novel combination, construction, and arrangement of parts, as hereinafter described and claimed.

Referring to the accompanying drawing, A represents a water-closet bowl; B, the retainer, 35 and C the lever for operating the pan, clapper or valve, and the water-cock in the customary way, and to which is attached a push-rod, D. Said parts may be constructed and arranged in the usual or any other desired and suitable 40 manner, and need not therefore be more particularly described.

D represents a tank or reservoir designed and adapted to receive a disinfectant of any suitable character, and which may be located 45 in any desirable place in the building or apartment furnished with the closet. From said reservoir leads a pipe, E, having a valve, e, and connects with another reservoir, D', which is made of a size about large enough to hold the 50 desired charge of disinfectant designed to be passed into the bowl or its container. The lat-

ter is connected to reservoir D' by a pipe, E', the bore of which is much smaller than the passage-way through cock e, so that a charge of disinfectant passing into reservoir D' cannot flow out of the same as fast as it enters, but will be held therein for an interval of greater or less duration, depending upon the difference between the bore of pipe E' and the opening in the cock e. The latter is provided 55 with a crank or handle, e', which is operated to open and close said valve by means of collars f f on rod F, secured to lever C.

d represents an air pipe or vent for reservoir D', and the bowl A is designed to be provided 60 with the usual or other seal, as indicated at x.

The operation is as follows: When rod D is raised to effect the flushing of the bowl the valve e is opened, the disinfectant from reservoir D flows through pipe E into tank D', and thence by way of pipe E' to container B; but as the bore of pipe E' is less than that of valve e, it follows that the disinfectant cannot flow out of tank D' as fast as it enters the same. Hence but a small portion of the disinfectant 70 enters the container when the flushing-water from the bowl is passing therethrough. The greater portion of the charge of disinfectant is therefore held in tank D' until after the flushing operation is completed, when it gradually 75 flows into the container, and from thence to the trap of the closet, (shown by dotted lines y y.) The disinfectant flowing in a gentle stream into the trap, the latter is not siphoned, and the advantages designed to be derived from the 80 use of the disinfectant are therefore obtained in the fullest degree.

I have shown and described my invention as applied to water-closets having a container; but it is obvious that it is equally applicable to 90 closets wherein the container is dispensed with, in which case the pipe E' will connect with the bottom of the bowl, or just below the sealing-valve therefor, if such valve is used; or said pipe may connect with the trap of the closet 95 or to other fixtures. So, too, I have shown the reservoirs D D' separate from each other; but it is obvious that they may be combined to form one reservoir having two compartments, with the cock e intervening.

100 What I claim as my invention is—

1. In combination with a water-closet, the

reservoirs D D', pipe E, having cock e, and operating mechanism therefor, and the outlet or connecting pipe E', substantially as shown and described.

5 2. A disinfecting device for water-closets, composed of two reservoirs, with intervening pipe, E, and a cock and operating mechanism therefor, and an outlet-pipe the bore of which

is less than the passage-way through the said pipe E, substantially as shown and described. 10

In testimony whereof I affix my signature in presence of two witnesses.

CHARLES F. PIKE.
